UNITED STATES PATENT OFFICE.

JACOB RUBIN, OF PHILADELPHIA, PENNSYLVANIA.

GARMENT.

1,340,915.

Specification of Letters Patent. Patented May 25, 1920.

Application filed August 6, 1919. Serial No. 315,581.

To all whom it may concern:

Be it known that I, JACOB RUBIN, a citizen of the United States, residing at Philadelphia, in the county of Philadelphia and State of Pennsylvania, have invented certain new and useful Improvements in Garments, of which the following is a specification.

It is well known that prior to my present invention that one-piece knitted bathing suits, or bathing suits in which the body portions are connected to the leg portions, have not been desirable for the reason that when the suits become wet the water drains to the bottom of the garment causing increased weight at the bottom of the garment which acts to sag or pull the crotch portion of the garment away from the crotch of the wearer, thereby producing a baggy and uncomfortable feeling, the same also being unsightly in appearance. With the exception of the above mentioned fault a one-piece bathing suit is especially desirable since it prevents any separation at the waist line between the body portion and the leg portion as occurs when bathing suits made of separate body and leg portions are worn.

One object of my invention is to prevent the above mentioned bagging, or dropping of the crotch of a one-piece bathing suit or suit in which the body portion is connected to the leg portion, thereby enabling a person to enjoy the advantage of a one-piece suit without the above mentioned discomfort. Another object is to so construct my invention that it can be made quickly and cheaply and will be durable.

These objects, and other advantageous ends which will be described hereinafter, I attain in the following manner, reference being had to the accompanying drawings in which—

Figure 1 is a front elevation of a one-piece bathing suit made in accordance with my invention,

Fig. 2 is an enlarged sectional elevation taken on the line 2—2 of Fig. 1,

Fig. 3 is a fragmentary enlarged elevation showing a portion of my improved bathing suit looking at the inner face of the back of said bathing suit, and

Fig. 4 is an enlarged section taken on the line 4—4 of Fig. 3.

Referring to the drawings, my improved

bathing suit 5 includes integral body and leg portions 6 and 7 which are made of knitted fabric, such for example as knitted worsted, the leg portions having a closed crotch 8. The garment is preferably open down to the waist line, as shown at 9, and may be provided with any fastening means, such for example as the buttons 10. A collar 11 extends across the back 12 and downwardly to form the opening 9 in the front, as clearly shown in Fig. 1. A strip 13, which is preferably made of a woven fabric including warp and weft threads, is sewed by stitching 14 adjacent each of its edges 15 to the inner face 16 of the back 12. The strip 13 extends down the back 12 from the collar 11 to the crotch 8. This strip 13 is of sufficient strength throughout its length to prevent the knitted material between the crotch 8 and the collar 11 from stretching, due to the weight of the water capable of being absorbed by the suit when worn in the water. In other words, the strip 13 is non-stretching or cannot be stretched in the direction of its length by the weight of water absorbed by the knitted body and leg portions 6 and 7 of the garment. In some instances, such for example as in children's garments, I prefer to make the strip 13 of material which is in itself non-stretching in the direction of its length. In other instances, however, such for example as in adults bathing suits, I can make the strip 13 of a strong piece of elastic fabric, such for example as the elastic fabric used in the making of men's suspenders. However, whether a completely non-stretching strip is used or whether an elastic strip is used, it will be understood that the strip 13 is non-stretching in the direction of its length, due to the weight of the water absorbed in the garment. The advantage in having the strip 13 made of elastic material is that it permits the wearer of the bathing suit to bend over without any uncomfortable result, since even though the elastic strip would be incapable of stretching to permit the crotch to drop or sag, due to the weight of absorbed water in the knitted fabric, it is capable of temporarily stretching, due to the muscular action of the body of the wearer when the wearer stoops over. However, I preferably make the strip 13 of non-stretching cloth, such for example as woven cotton, silk, linen

or the like, since under ordinary conditions sufficient slipping is permitted to allow a person to move the body without any uncomfortable feeling.

5 The fact that the strip 13 extends from the uppermost part of the body portion to the crotch and also the fact that the suit is supported on the shoulders of the wearer serves to prevent the stretching of the portion 10 of the suit to which the strip 13 is secured and always holds said portion in a similar position with respect to the shoulders of the wearer. Thus the crotch 8, being connected to said non-stretching strip, will 15 always be held in the same position with respect to the shoulders of the wearer and no matter how much water is absorbed by the suit, the weight of that water cannot pull the crotch 8 away from the crotch of 20 the wearer and the garment therefore always fits neatly and snugly and is always comfortable. Further than this, the suit is held in shape so that it is always neat in appearance.

25 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come 30 within the scope of the appended claims.

Having thus described my invention, what I claim as new and desire to secure by 35 Letters Patent is:—

1. A closed crotch knitted garment having integral knitted body and leg portions; and a strip secured to said garment adjacent its back and extending downwardly to the 40 crotch, said strip being of sufficient tensile strength in the direction of its length to prevent the crotch from moving downward to an unsightly or uncomfortable position relative to the shoulders of the garment due to 45 the weight of the garment when saturated with water; substantially as described.

2. A knitted garment having integral knitted body and leg portions; and a strip secured to said garment and extending down 50 the back thereof from a position adjacent the top of the garment to the crotch, said strip being of sufficient tensile strength in the direction of its length to prevent the crotch from moving downward relative to 55 the shoulders of the garment due to the weight of the garment when saturated with water; substantially as described.

In testimony whereof I have signed my name to this specification in the presence of 60 two subscribing witnesses.

JACOB RUBIN.
